UNITED STATES PATENT OFFICE.

WALTER S. COH, OF BROOKLYN, NEW YORK, ASSIGNOR TO MERGENTHALER LINOTYPE COMPANY, A CORPORATION OF NEW YORK.

TYPE OR MATRIX.

1,099,488.

Specification of Letters Patent. Patented June 9, 1914.

Application filed October 31, 1912. Serial No. 728,777.

To all whom it may concern:

Be it known that I, WALTER S. COH, a citizen of the United States, and a resident of Brooklyn, county of Kings, and State of New York, have invented a new and useful Improvement in Type or Matrices, of which the following is a specification.

My invention relates to typographical machines, such as linotype machines of the general organization presented in Letters Patent of the United States to O. Mergenthaler, No. 436,532, wherein circulating matrices are released from a magazine in the order in which their characters are to appear in print and then assembled in line, the composed line transferred to the face of a slotted mold, the mold filled with molten metal to form a slug or linotype against the matrices which produce the type characters thereon, and the matrices thereafter returned through a distributing mechanism to the magazine from which they started.

More particularly, it relates to the matrix or matrix supporting element, and its general object is to permit variation in the position of the type characters edgewise of the slug, toward its upper or its lower side as the case may be. This capability is advantageous for a variety of reasons,—for instance, in order to accommodate accents or characters having an unusual length above or below their body portions, or again, in connection with advertising matter and matter surrounded by borders or rules, which have to be joined at their corners. Such longitudinal variation has been ordinarily provided for in the past by the employment of an adjustable keeper-plate or alining bar to engage the ears of the matrices, and which may be moved toward or away from the mold slot at will, and to any desired extent, as shown for instance in Letters Patent of the United States to J. R. Rogers, No. 846,053, dated March 5th, 1907.

To accomplish a similar result, I now arrange the matrix in such manner that the operative position of its character may be varied with reference thereto, and preferably I construct it so that its alining ear is adjustable with reference to the other parts thereof, as will be hereinafter described. It will be seen also that in this way the position of a single character may be varied with reference to the others in the same line, if desired, due to the adjustability of the individual

matrix, which result does not inhere in the previously-mentioned Rogers construction, wherein it is necessary to move the alining bar or keeper-plate as a whole and thus to adjust simultaneously all the characters in the line. 60

In the accompanying drawing, I have shown my invention in preferred form and by way of example, and as applied to the ordinary commercial linotype matrix, but obviously many variations and modifications thereof, and in its mode of application, will be possible and still be comprised within its spirit. Thus for instance it may be applied to other kinds of typographical machines, 70 and also to types or dies, which are formed with male characters, instead of intaglio ones as in the form illustrated.

Generally speaking, I desire it to be understood that I do not limit myself to any particular form or modification, except in so far as such limitations are specified in the claims. 75

Referring to the drawing: Figure 1 is a perspective view of a linotype matrix, having my invention applied thereto; Fig. 2 is a transverse vertical section thereof; and Fig. 3 is a perspective view of a modification. 80

The matrix A is provided as usual with the projecting ears B and C, and with the intaglio character D, which forms the projecting letter on the slug. In order that the letter may be located differently on the edge of the slug, I provide means whereby the operative position of the character D 90 may be varied with reference to the effective or alining portions of the matrix itself. To this end, I preferably form the matrix with a deep slot or incision E in one edge thereof and in proximity to the alining ear C, which determines the relation of the character D to the mold slot. Due to this cut or incision, the ear C may be moved or sprung relatively to the remainder of the matrix, and in this manner the operative position of the character D is correspondingly varied. The screw F, passing through the lower portion of the matrix, across the incision E, and into the matrix body, affords a convenient means for adjusting the ear C to the desired extent. 100

In Fig. 3, I have shown an adaptation of my invention to the well-known "quad-block" A', having the longitudinal groove G to receive and hold a matrix strip H, such 110

as is ordinarily used for rules, borders, dashes and the like. In this instance, the block A¹ is similarly formed with the alining ear or ledge C¹, the notch or incision E¹, and one or more adjusting screws F¹.

As previously stated, I have shown my invention in preferred form and by way of example, but obviously many variations and alterations therein will suggest themselves to those skilled in the art without departure from its scope.

Having thus described my invention, its construction and mode of operation, what I claim and desire to secure by Letters Patent of the United States is as follows:

1. A type or matrix having a printing character located between its ends and formed so that the character may be set permanently in different operative positions relatively to one of its ends.
2. A type or matrix formed with a printing character and provided with means whereby the printing character may be set permanently in different operative positions longitudinally of the type or matrix.
3. A type or matrix formed with a printing character and an alining portion, and means whereby the vertical operative position of the character may be varied relatively to the alining portion.
4. A type or matrix formed with a printing character and an alining ear, and means whereby the vertical operative position of the character may be varied relatively to the alining ear.
5. A type or matrix formed with a print-

ing character and comprising a plurality of portions which may be set permanently in different positions relatively to each other lengthwise of the type or matrix, whereby the operative position of the character may be varied.

6. A type or matrix formed with a printing character and provided with adjusting means movable relatively to the part of the matrix upon which the character is formed whereby the latter may be moved to and held in different operative positions longitudinally of the type or matrix.

7. A type or matrix comprising a body portion provided with a printing character and an alining portion, the said alining portion being formed so as to be adjustable relatively to the body portion.

8. A type or matrix comprising the body portion A having the character D and the alining ear C, and formed with the incision E to permit of the adjustment of the ear relatively to the body portion.

9. A type or matrix provided with a printing character and an alining portion together with means whereby the alining portion may be set at different vertical distances from the printing character.

In testimony whereof I hereunto set my hand this 28th day of October, 1912, in the presence of two attesting witnesses.
